UNITED STATES PATENT OFFICE.

FRANÇOIS BRAULT AND ANDRÉ CORDIER, OF LEVALLOIS-PERRET, FRANCE.

BRAKE MECHANISM.

Application filed October 12, 1927, Serial No. 225,773, and in France October 13, 1926.

This invention relates to improvements in brakes of a known type comprising a metallic band coiled into circular form and which is pressed by separating its extremities 5 against the wall of a drum in rigid connection with the mechanism which it is desired to stop.

Fig. 1 of the accompanying drawings shows in diagrammatic elevation a brake of this 10 known type.

A is the ribbon or band adapted to be pressed against the inner wall of the drum B which is fixed to the rotary mechanism. This band is pivotally connected at its extremities A¹, A², to rods, adjustable as to length, C and D respectively. The displacements of these rods in opposite directions are caused by the manipulation of the key or controlling device E. Rigid members such as right angle 15 pieces F—F¹ and G—G¹, attached by one arm F¹, G¹ to the band, guide this latter, at its middle part by means of the other arms F, G on each side of a fixed support H. The clamping or braking action is obtained by a 20 rotation of the key in the direction of the arrow, Fig. 1, the rods or links C, D causing forces to be produced which separate the extremities A¹, A² of the band, forcing them apart as shewn at Fig. 2. This band being 25 rigidly guided at its middle portion, is forced by this latter against the drum B. But when the drum turns, for instance in the opposite direction to the hands of a watch, that is to say in the opposite direction to the manipulating key, only the right hand portion 30 of the band comprised between the fixed support H and the extremity A² tends to rest pressed against the drum, as shewn by the arrow at 1 in Fig. 2, the portion on the left H—A¹ tending, on the contrary, to become loose, as shewn by the arrow at 2 in Fig. 2. The result is that there is a clamping or braking action which is not progressive and which is incomplete, only one of the 35 halves of the band producing an effective braking, in whichever direction the drum may be rotating.

The improvements, forming the object of the present invention, entirely obviate this 40 drawback and allow for a braking action which is altogether progressive and complete to be exerted by the band upon the drum.

According to the invention, the band is 45 guided in a rigid radial guide formed in the fixed portion, the guiding being effected by means of suitable flexible fingers constituted,

for example, by one of the arms of a right angled or like piece, of which the other arm is attached to the band. This is the constructional embodiment of the invention which is 50 represented by way of example in the accompanying drawings.

In these drawings, as previously stated, Figs. 1 and 2 are diagrams illustrating known constructions.

Fig. 3 shews the improved braking device, constructed according to the invention, in side elevation in the inoperative position.

Figs. 4 and 5 are part sections respectively on 4—4 and 5—5 of Fig. 3.

Fig. 6 is a part sectional elevation corresponding to Fig. 3, shewing the parts in the operative position for braking.

Figs. 7 and 8 and 9 are diagrams illustrating the operation of the apparatus.

In these figures, A denotes the band, of steel, covered for instance by a band of ferodo *a*, and of which the extremities A¹, A², are pivotally connected to links C, D of adjustable length, the pressure or push being 55 produced in a known manner, by means of buttons *e* of a key *E*. B denotes the drum rigidly connected to the rotary element, such as a wheel of a vehicle for example.

According to the invention, the band is 60 guided at its middle portion, by means of radial flexible fingers F, G, constituted for instance by the free arms of two right angle pieces, the other arms of which F¹, G¹ are fixed to the band. The guiding is ensured 65 by the arrangement of these fingers in a radial guide, constituted for example by a clip. In the example shewn, the branches of the clip are formed by projecting arms I¹ projecting from the fixed portion I and the 70 base of the clip is formed by a cap J fixed to the branches by means of screws *j*.

The flexible fingers F, G between which a suitable space is left, rest on small steel plates K connected to the arms I¹ of the clip by 75 means of screws *k*. At the free extremity of one of the flexible fingers at F is fixed one of the ends of a radial return spring L, the other extremity of which is attached to a button I² projecting from the fixed disc I (or 80 plate I).

If the key *E* is manoeuvred or turned, the extremities A¹ and A² of the band which, in the out of use position, are in the position shewn in Figs. 3 and 7, are moved away from 85 one another, and the opening out of the band tends immediately to produce a clamping or

braking action of the flexible fingers F, G against the plates K. However, the flexibility of the fingers and the space for play provided between them allows them to be come slightly out of shape, by resting on the plates and this allows in general for the band after it has come to rest on the drum (Fig. 8) to move with this latter for a short time during its movement of rotation; as shewn in Figs. 6 and 9. The braking points of the band on the drum which were originally at 1, 1, Fig. 6, move to 2, 2. Lastly, the band in place of being separated from the drum, by the portion to the left thereof, maintains contact on the contrary, and progressively, with the wall, and this adherence is a direct function of the velocity of rotation of the drum.

The employment of flexible radial fingers and the method of guiding them on the interior of the guide against the walls of the parts from which they might receive support at the same time that one is supported by the other, by reason of the small separation or space left between them, permits, as will be seen from the beginning of the clamping an angular movement of the band in the direction of rotation of the drum. This movement permits of the compensation for the slight variations of length of the rods C and D, and it ensures above all, as has been seen, the adhesion of the band as a whole with the inner wall of the drum, whatever may be the direction of motion or rotation of the drum.

The radial guiding of one of the fingers in the immediate neighbourhood of the other finger allows, on the one hand, for ensuring the return by a radial spring attached to one of the two fingers.

What we claim and desire to secure by Letters Patent of the United States of America is:—

1. A band brake for the wheels of vehicles and for other purposes comprising a metallic band the extremities of which are pivoted to rods of adjustable length controlled, in order to separate the extremities, by a key; characterized by the fact that the guiding of the middle portions of the band with respect to a fixed portion is effected by means of flexible radial fingers in rigid connection with the band and kept at a slight distance apart on the interior of a radial fixed guide so that on the radial displacement of the fingers due to the separation of the extremities of the band, their transverse flexion may follow by contact with the walls of the guide and mutual contact between the fingers under the effect of the movement of the band by the drum.

2. A constructional form of mechanism as claimed in claim 1 in which the flexible fingers are constituted each by one of the arms of a right angled member of which the other arm is attached to the band, the guide being formed by a clip the arms of which are provided with steel plates which serve for supports for the fingers and which are covered in by a cap, the free extremity of one of the fingers serving for attachment of one of the extremities of a radial return spring connected by its other extremity to a fixed button.

3. In brake mechanism of the type described, a construction including a hollow drum, a circular split band, means for separating the ends of the band, a flexible projection at the middle of the band and fixed means co-operating with the flexible projection to restrain its movement in either direction substantially as and for the purposes set forth.

In witness whereof we affix our signatures.

FRANÇOIS BRAULT.
ANDRÉ CORDIER.
